UNITED STATES PATENT OFFICE.

ANDREW S. KNAPP, OF KANSAS CITY, MISSOURI.

HAIR RETAINER.

Application filed May 5, 1924. Serial No. 710,963.

This invention relates generally to hair retainers, and particularly to a hair retainer which may be used by men and boys to retain their hair in a smooth condition while said hair is drying after being washed. As is well known, it is a common practice in barber shops to wrap a cloth or a towel about the head of a person whose hair has just been washed, the idea being that the cloth will absorb most of the dampness from the hair and will aid the drying operation. While this method has been employed for many years, the desired results are not always obtained by its use due to the fact that the air is prevented by the cloth or towel from coming into contact with the damp hair. Consequently, instead of aiding the drying operation the use of a cloth or towel in the manner described retards the drying operation. By the use of the hair retainer disclosed in the present application, the hair is retained in a smooth condition during the drying operation, and because said hair retainer is made largely of open-woven fabric, such as netting, the air is permitted to contact with the damp hair to accomplish a thorough drying of the hair in a comparatively short time.

My hair retainer is also intended for use in training the hair of young boys, said hair retainer being capable of being worn in lieu of a cap.

Fig. I is a perspective view of my improved hair retainer, said hair retainer being shown in place on the head of a man as indicated by dotted lines.

Fig. II is an enlarged front view of my hair retainer.

Fig. III is an enlarged fragmentary view showing the manner of attaching the securing members of my hair retainer to the body portion thereof.

In the drawings A designates my improved hair retainer, which comprises a body portion 1, preferably formed of open-woven fabric such as netting, said material resembling the material of which ladies' hair nets are made but the individual strands thereof being much heavier and stronger than the strands of the hair net material. The body portion of my improved hair retainer is shaped to fit the upper portion of a person's head and is provided with a depending portion 2 at the rear of said body portion which is intended to cover the back of the

wearer's neck. Secured to the body portion 1 and the depending portion 2 at their lower edges is a reinforcing strip 3, said strip being extended throughout the length of the lower edges of said portions. The strip 3 60 may be stitched or otherwise secured to the body portion 1 and the depending portion 2, and by its use the lower edge of the hair retainer is given the required strength to withstand the handling to which it may be 65 subjected. To further reinforce the hair retainer, I employ a second strip 4 which extends parallel with that portion of the strip 3 which is located at the front of the hair retainer, said strip 4 like the strip 3 70 being stitched or otherwise secured to the body portion 1, and the opposite end portions of said strip 4 being inclined toward the strip 3 (Fig. I).

Located at each side of the hair retainer 75 is an upwardly extending reinforcing strip 5, said strips 5 being located at the points where the strips 3 and 4 are very close together and said strips 5 being secured to said strips 3 and 4 and to the body portion 1. 80 Arranged over the top of the hair retainer is a longitudinal reinforcing strip 6, said strip 6 being extended from the strip 3 at the front of the hair retainer to that portion of said strip which is located at the lower 85 edge of the depending portion 2. The longitudinal strip 6 is secured to the strip 3 at the front and rear of the hair retainer and to the body portion 1 thereof by means of 90 stitches.

Secured to each of the strips 5 is a securing member 7, each of said securing members being preferably formed of a strip of elastic material 8 which is enclosed within a covering of fabric 9, said fabric cover being of 95 sufficient length to permit stretching of the strips of elastic material 8. One of the members 7 is provided with a suitable hook 10 and the other member 7 is provided with an eye 11 adapted to receive said hook 10, 100 whereby the free ends of said members may be attached together.

In the use of my improved hair retainer, after the hair has been combed said hair retainer is drawn over the head to the position in which it is shown in Fig. I of the drawing. The free ends of the securing members 7 are then attached together in the manner illustrated, whereby the marginal edge of the hair retainer is drawn tightly 110

about the head of the wearer, thus preventing said hair retainer from being accidentally displaced.

It is apparent that when the hair retainer disclosed herein is in place, as described, on the head of a person, the air may pass freely through the body portion 1 to dry the hair of said person, and because of the use of the reinforcing strips 3, 4, 5 and 6 it is plain that the comparatively frail body portion will be given the necessary durability.

I claim:

A hair retainer comprising a continuous body of open-woven fabric shaped to fit a person's head, a reinforcing strip secured to and extending throughout the length of

the lower edge of said body, a second reinforcing strip extending around the forward portion of the body and having its ends in contact with the first-mentioned strip, rearwardly extending elastic strips secured to the ends of said second strip, coverings of fabric enclosing said elastic strips and of sufficient length to permit said elastic strips to stretch, fastening means secured to the rear ends of said elastic strips, and reinforcing strips secured to opposite sides of the body and at their lower ends to the juncture of the above-mentioned strips.

In testimony that I claim the foregoing I hereunto affix my signature.

ANDREW S. KNAPP.
